UNITED STATES PATENT OFFICE.

JOSEPH W. KAYS, OF EUGENE, OREGON.

PITMAN CONNECTION.

1,174,324.

Specification of Letters Patent.

Patented Mar. 7, 1916.

Application filed October 6, 1913. Serial No. 793,646.

To all whom it may concern:

Be it known that I, JOSEPH W. KAYS, a citizen of the United States, residing at Eugene, in the county of Lane and State of Oregon, have invented certain new and useful Improvements in Pitman Connections, of which the following is a specification.

This invention relates to pitman connections and while the connection embodying the present invention is designed primarily for use with the head of a knife bar of a mowing machine, it is not limited to such use but may be employed in various mechanisms.

15 The invention aims to supply a novel connection between the pitman and the knife head of a mowing machine, thereby admitting of the coupling and uncoupling being readily effected and the joint automatically compensating for wear and variations, so as to obviate looseness and rattle and to insure positive movement of the knife bar without any play or lost motion, which is objectionable for various reasons.

25 The invention is designed more particularly as an improvement on the pitman connection shown in Patent No. 935,140, issued September 28, 1909, to W. L. Chrysler and myself, one feature of improvement residing 30 in the provision of means for varying the leverage which may be brought to bear when the socket members of the connection are closed about the head of the knife bar or other element to be driven, the connection 35 being in this manner adapted for employment with knife bars of various types and having different sizes of heads and being further better adapted to compensate for wear.

40 In the accompanying drawings: Figure 1 is a plan view of the connection embodying the present invention. Fig. 2 is a horizontal section therethrough. Fig. 3 is a transverse sectional view of the line 45 3—3 of Fig. 2. Fig. 4 is a perspective view of the fulcrum for the lever which is provided for closing the socket of the connection. Fig. 5 is a perspective view of the socket members detached.

50 In the drawings the pitman proper is indicated by the numeral 1 and the connection therefor consists essentially of two socket members, one indicated by the numeral 2 and the other by the numeral 3. These socket members are provided with at-

taching portions or shanks 4 secured to opposite sides of the pitman 1 by rivets or bolts 5 in the manner clearly illustrated in Figs. 1 and 2 of the drawings. The member 3 is relatively rigid but, as will be observed from an inspection of Fig. 2, the member 2 is sprung slightly from that side of the pitman 1 to which it is connected, as indicated at 6, so that it will possess the desired degree of resiliency adapting it to be sprung toward the socket member 3 in order to close the socket members about the ball member of the connection which is indicated in general by the numeral 7. The members 2 and 3 are formed respectively at their ends which project beyond the end of the pitman 1, with sockets or cupped heads 8 and 9, the concave sides of which are, of course, presented toward each other. The member 2 is formed with a slot 10 and with a bail 11 extending transversely of the slot. This bail 11 constitutes a connection for the closing lever of the device as will be presently explained.

55 The socket member 3 is formed directly opposite the slot 10 with a slot 12 and the lever above mentioned and indicated in the drawings by the numeral 13, has an angularly extending end portion 14 terminating in a hook 15, the portion 14 being inserted through the slots 12 and 10 and the hooked end 15 being engaged with the bail 11 in the manner clearly shown in Fig. 2.

60 The body portion of the lever is provided with a handle portion 16 which is tapered in the direction of its free end whereby it will possess the desired degree of resiliency and the said portion is formed at its extremity with a short bend 17 over which may be engaged a keeper yoke 18 65 pivoted as at 19 at that side of the pitman opposite the side adjacent to the handle portion of the lever, as shown in Fig. 1, it being understood that the keeper yoke serves to hold the lever when the latter is swung to close the socket of the connection.

70 The fulcrum for the lever is clearly illustrated in Figs. 2 and 4 of the drawings and is preferably in the nature of a yoke freely slidable upon the body portion of the lever, 75 the opposite sides of the yoke, indicated one by the numeral 20 and the other by the numeral 21, constituting the fulcrum portions upon which the lever is to be rocked. It will be observed that the portion 20 is of less 80

height than the portion 21 and it may here be stated that the yoke is reversible upon the lever as well as slideable thereon so that either of its said portions 20 or 21 may be positioned between the body portion of the lever and the outer side of the socket member 3, depending upon the degree of leverage desired to be secured. In order that the yoke when adjusted upon the lever may be held against accidental displacement, that side of the body portion of the lever which is presented toward the socket member 3 is formed with a series of notches 22 in which the fulcrum portions 20 or 21 may be inter-
changeably engaged. Inasmuch as the notches 22 extend in a series lengthwise of the body portion of the lever it will be understood that by adjusting the yoke toward the end 14 of the lever the leverage may be increased and it will also be understood that when the fulcrum portion 20 is in position between the lever and the socket member 3, the leverage will be less than when the portion 21 is so positioned. It will be understood, therefore, that by reversing and slideably adjusting the fulcrum yoke shown in Fig. 4, upon the body portion of the lever, a fine degree of adjustment of leverage may be secured and the socket members may, therefore, be caused to grip the head 7 or other element with which they are engaged, with exactly the desired degree of firmness and without so binding as to render the connection stiff, or so loose as to permit of rattling.
While the employment of a fulcrum such as shown in Fig. 4, adjustable as shown and described, will allow of considerable latitude of adjustment of leverage and therefore adapt the connection for use with heads of various sizes, it will at times be found desirable or necessary to secure a finer adjustment than can be obtained by the use of said fulcrum. For this purpose there is provided an adjusting screw 23 adjustably threaded through an opening 24 in the member 3 and adapted to serve as a fulcrum for the lever, this screw being provided at its end, which is located between the members 2 and 3, with a head 25 by means of which it may be adjusted and having threaded upon it a set nut 26 which may be tightened to hold it at adjustment. By the use of this screw it will be apparent that a fine degree of adjustment can be secured so that the

head 7 will be engaged with exactly the desired degree of firmness.

It will be understood that the connection is equally well adapted for a new head or for a head that has been in use and whose bearing member has become worn. It will be apparent that when the link is disengaged from the lever, the socket members will automatically separate or spread, thereby releasing the ball of the bearing member and admitting of the pitman being quickly and easily disconnected from the knife head.

Having thus described the invention, what is claimed as new is:

1. In a pitman connection, socket members, one of said members being provided with a bail and the other member being formed with a slot, a lever for closing the socket members having an angularly extending end provided with a hooked terminal engaged with said bail, the said end of the lever extending through the said slot, and a set screw adjustably threaded through the member in which the slot is formed and located relatively close to one end of the said slot, the said set screw constituting a fulcrum for the lever and being adjustable to project its fulcrum end a greater or less distance beyond the outer side of the member in which it is mounted.

2. In a pitman connection, socket members, one of said members being provided with a bail extending transversely of a slot therein, the other member being formed with a slot, a lever for closing the socket members having an angular hooked end inserted through the slot in the second mentioned member and engaged with the said bail, means removably engaged with the end of the lever for holding the same in position beside the second mentioned member, and a screw, threaded through the second mentioned member and bearing at its end against the inner side of the lever near the hooked end thereof, the head end of the screw being housed between the said members.

In testimony whereof I affix my signature in presence of two witnesses.

JOSEPH W. KAYS. [L. s.]
